SURFACE DRESSING MACHINE

Alfred Iobbi, Trevose, Pa.

Application July 2, 1951, Serial No. 234,713

6 Claims. (Cl. 51—177)

1

This invention relates to surface dressing machines adapted to be used for sanding and polishing wooden floors, stair treads, risers, and similar surfaces.

Heretofore the devices commonly used for finishing surfaces such as floors, and the like, usually comprised, as essential parts, a sanding disc and electric motor for rotating the same.

However, such machines, in most instances, were constructed and arranged so that it was not possible to apply the abrasive disc to certain surfaces such, for example, as the portions of the floor under radiators, and with those machines which were specially designed for the purpose of getting under radiators and in other confined spaces, it was not possible to handle the same expeditiously and conveniently and to properly apply the necessary pressure when one of the machines was being used upon the ordinary expanse of the floor.

The principal object of the present invention is to provide a machine for finishing surfaces having a novel arrangement of parts and which is so constructed and arranged as to facilitate the operations and extend the scope of usefulness thereof.

A further object of the invention is to provide a machine of the character aforesaid the parts of which may be readily and quickly shifted to permit the convenient use of the same under varying conditions.

The nature and characteristic features of the present invention will be more readily understood from the following description, taken in connection with the accompanying drawings forming part hereof, in which:

Figure 1 is a top or plan view of a surface dressing machine embodying the main features of the present invention;

Fig. 2 is a vertical section thereof, taken on the line 2—2 of Fig. 1, the motor however being shown in elevation;

Fig. 3 is an underneath plan view of the machine; and

Fig. 4 is a transverse section taken approximately on the line 4—4 of Fig. 1.

It should, of course, be understood that the description and drawings herein are illustrative merely, and that various modifications and changes may be made in the structure disclosed without departing from the spirit of the invention.

Referring to the drawings, in the particular embodiment of the invention therein shown, 10 is an electric motor, of any preferred type, pro-

2

vided with a main handle 11 projecting at right angles to the axis of the motor 10 and through which handle the lead-in wires 12 extend.

The motor 10 may also be provided with an auxiliary handle 13 which is adapted to be alternatively mounted on either side of the motor housing as may be desired, but in either event extending at a right angle to the handle 11 and in the same or a parallel plane.

10 The housing of the motor 10 is provided with an extension 14 in which the reduction gearing (not shown) may be enclosed, and from which an operating shaft 15 extends downwardly. A pulley 16 is mounted on the lower end of the shaft 15.

The lower end of the extension 14 of the housing of the motor 10 is provided with an annular flange 17 which rests upon the top surface of a casing 18 which projects outwardly therefrom.

20 A plate member 19 having an annular recess 20 therein engages the flange 17 of the extension 14 of the housing of the motor 10. The plate member 19 is secured to the casing 18 by means of bolts 21, 22, and 23, which extend through 25 elongated slots 24, 25, and 26, respectively, in the casing 18. The bolts 21 and 22 are threaded into angle members 27 having vertical extensions 28 which engage the inner faces of the side walls 29 of the casing 18.

The bolt 23, which is arranged at the central rear portion of the casing 18 is secured by means of an ordinary nut 34 threaded on said bolt 23.

The plate member 19 which serves to confine the flange 17 of the extension 14 of the housing 35 of the motor 10 is also provided at the two rear corners with casters 30 secured at their respective locations by nuts 31 threaded on the shank portions 32 of the casters 30.

At the forward end of the extending casing 18 there is mounted an auxiliary casing 35 in which the abrasive disc and the associated parts are rotatably mounted.

Secured to the auxiliary casing 35 is a cup member 36 which serves to support the outer ring 37 of a ball bearing. The inner ring 38 of the ball bearing is mounted on a stud shaft 40, the free end of which has a metallic disc 41 threaded thereon.

The disc 41 has a rubber facing member 42 upon which the abrasive disc 43 is mounted. The abrasive disc 43 is of the usual type, being made of paper or cloth with a granular abrasive secured on its face, and the same is secured to the rubber faced metallic disc 41 by means of a nut 44 threaded on the stud shaft 40.

Secured to a portion of the supporting disc 41 is an annular member 45 suitably shaped to provide, in conjunction with a suitably shaped face portion of the disc 41, an annular channel 46 in which the belt 47 travels to rotate the abrasive disc 43 and its associated parts. The belt 47 is driven by the pulley 16 on the shaft 15 which is operated by the motor 10.

The bolts 21, 22 and 23 are ordinarily of such tension that the casing 18 and the parts carried thereby may be swung with a certain degree of frictional restraint, about the axis of the shaft 15, whereby the main handle 11 which is secured to the motor housing, may be disposed at any desired angular position with respect to the extending casing 18.

When, however, it is desired to lock the handle 11, as well as the auxiliary handle 13, in any desired adjusted position this may be accomplished by tightening the bolts 21, 22 and 23 sufficiently to securely clamp the flange 17.

The arrangement is also such that, by loosening the bolts 21, 22 and 23 sufficiently, the casing 18 may be shifted longitudinally with respect to the motor 10 and its associated parts, including the pulley 16, to take up any slack in the belt which may be necessary to cause the abrasive disc to be rotated efficiently.

It will be seen that there is thus provided a surface dressing machine in which by a relatively simple arrangement the abrasive mechanism proper may be swung to any desired position with respect to the main handle of the motor, thereby greatly extending the usefulness of the tool.

It will also be noted that the arrangement is such that the proper belt tension may be readily obtained by the mere longitudinal shifting of the extending casing with respect to the motor and its associated parts, and this may be controlled by the same means which control the shiftability of the handle with respect to the extending casing in which the abrasive disc and its associated parts are mounted.

I claim:

1. A surface dressing machine comprising an electric motor, a handle fixedly secured to and extending outwardly from the side thereof, a relatively low extending casing, means for rotatably securing a portion of the motor to one end of said extending casing whereby the handle carried by the motor may be brought to desired angular relationship with respect to said casing, an abrasive disc journaled at the other end of said casing, and driving means operated by the motor for rotating said abrasive disc.

2. A surface dressing machine comprising an electric motor, a handle fixedly secured to and extending outwardly from the side thereof, the motor having a housing with a portion provided with an annular flange, a relatively low extending casing, means for securing the annular flange of the motor housing to one end of said extending casing whereby the motor handle carried by the motor may be brought to desired angular relationship with respect to said casing, an abrasive disc journaled at the other end of said casing, and driving means operated by the motor for rotating said abrasive disc.

3. A surface dressing machine comprising an electric motor, a handle fixedly secured to and extending outwardly from the side thereof, the

motor having a housing with a portion provided with an annular flange, a relatively low extending casing, a plate member engaging said annular flange for rotatably securing one end of said extending casing to the motor whereby the handle may be brought to desired angular relationship with respect to said casing, an abrasive disc journaled at the other end of said casing, and driving means operated by the motor for rotating said abrasive disc.

4. A surface dressing machine comprising an electric motor, a handle fixedly secured to and extending outwardly from the side thereof, the motor having a housing with a portion provided with an annular flange, a relatively low extending casing, a plate member engaging said annular flange for rotatably securing one end of said extending casing to the motor whereby the handle may be brought to desired angular relationship with respect to said casing, an abrasive disc journaled at the other end of said casing, and driving means operated by the motor for rotating said abrasive disc, said driving means including a belt enclosed in the extending casing.

5. A surface dressing machine comprising an electric motor, a handle fixedly secured to and extending outwardly from the side thereof, the motor having a housing with a portion provided with an annular flange, a relatively low extending casing, a plate member engaging said annular flange for rotatably securing one end of said extending casing to the motor whereby the handle may be brought to desired angular relationship with respect to said casing, an abrasive disc journaled at the other end of said casing, and driving means operated by the motor for rotating said abrasive disc, said driving means including a belt enclosed in the extending casing, and the casing being longitudinally adjustable with respect to the motor to regulate the tension of the driving belt.

6. A surface dressing machine comprising an electric motor, a handle fixedly secured to and extending outwardly from the side thereof, a relatively low extending casing adjustably secured at one end to a portion of the motor, an abrasive disc journaled at the other end of said casing, and driving means operated by the motor for rotating said abrasive disc, said driving means including a belt enclosed in the extending casing, and the means for securing the casing to the motor permitting the motor handle to be positioned in desired angular relationship with respect to the casing and also permitting the regulation of the tension of the driving belt.

ALFRED IOBBI.
